ABSTRACT OF THE DISCLOSURE

The file storage system includes spaced file items with metallic identification members, detector units responsive to the metallic members, and means to move the file items with respect to the detector units. Each detector unit includes a transducer head with a pair of coils in a circuit capable of oscillating, and each detector unit changes its state of operation after a metallic member is disposed in its sensing region. In between each file item, the detector units are reset to be ready to read the next file item. Consequently, the file storage system enables a desired file item to be identified although all its metallic members may not be simultaneously detected by the detector units.

The present invention relates to a file storage system and more particularly relates to a file storage system capable of identifying stored file items therein.

In file storage systems, many file items such as documents, cards, or papers, are systematically arranged in storage devices. At times, it is desirable to retrieve certain of the stored file items for temporary use and then replace them in the storage device. If a file storage system is used for arranging numerous items and if frequent temporary use is made of the stored items, then the process of locating the stored items becomes burdensome, and extraordinary care has to be taken to prevent and correct misplacement of the temporary used file items.

The file storage system incorporating the present invention includes a plurality of aligned detector units having metallic sensing regions spaced at preselected intervals. Each detector unit normally operates in a first state of operation and changes to another state of operation after a metallic member passes its sensing region. File items are provided with identification means having one or more aligned metallic members. The identification means of each file item may have metallic members arranged to represent an identifying number in binary form. After the identification means of each file item is moved by the detector units, an interval termination signal is produced to reset the detector units to their first states of operation preparing them to read the identification means of a subsequent file item. Common means are also provided including a plurality of switches capable of being selectively connected to the detector units to develop a coincident signal for a predetermined arrangement of the metallic members of the identifying means. When a coincident signal exists during an interval termination signal, the system develops a file item identifying signal.

It is therefore an object of this invention to provide a file storage system for identifying its stored film items.

Another object of this invention is to provide a file storage system wherein each file item has an identification means with identifying information in binary form.

An additional object of this invention is to provide a file storage system wherein each file item has an identification means with identifying information in binary form, and which includes means for quickly reading the identifying information of each file item.

A further object of this invention is to provide a file storage system having detector units to accurately read

2

the identifying information of each file unit passing in the proximity of the detector units without making physical contact therewith.

5 A still further object of this invention is to provide a file storage system wherein file items may be stored at random, and which includes detector units to accurately read the identifying information of each file item.

10 Still another object of this invention is to provide a file storage system wherein one or more of randomly placed files can be accurately quickly detected and selected.

15 Another object of this invention is to provide a file storage system having a plurality of aligned detector units having metallic member sensing regions to provide an identifying signal for a predetermined arrangement of metallic members wherein all the metallic members may not be simultaneously detected by the detector units.

20 Still another object of this invention is to provide a detector unit for an identifying system which reacts to a metallic member passing in the proximity thereof to change its operating state.

25 The novel features which are believed to be characteristic of the invention, both as to its organization and method of operation, together with further objects and advantages thereof, will be better understood from the following description considered in connection with the accompanying drawings in which an embodiment of the invention is illustrated by way of example. It is to be expressly understood, however, that the drawings are for the purpose of illustration and description only, and are not intended as a definition of the limits of the invention.

30 FIG. 1 is a side view of a file storage system incorporating this invention.

35 FIG. 2 is an enlarged view seen along lines 2—2 of FIG. 1 showing one of the file items with an attached identification means positioned under several detector units.

40 FIG. 3 is an enlarged showing of a side view of one of the magnetic transducer heads of the detector units seen in FIG. 2.

45 FIG. 4 is a partial perspective view of the file item seen in FIG. 2 with an attached metallic member and its associated transducer head.

FIG. 5 is a schematic circuit diagram of the electronics utilized in the system of the described embodiment.

50 Referring now to the figures, there is seen in FIG. 1 a side view of a file storage system incorporating this invention. An endless belt 10 is shown carried by pulleys 11a and 11b. An electric motor 12 is connected to rotate pulley 11a by belt drive belt 13 in order to move endless belt 10 around pulleys 11a and 11b in the direction shown by arrows 14a and 14b. A plurality of identical card holders, such as card holders 15a and 15b, are attached to the outer surface of belt 10. The card holders are seen to be spaced at approximate equal intervals along the circumference of belt 10. Each card holder carries a file item with an identification means such as file item 16a with identification means 17a in card holder 15a. A casing 18 for detector units is seen fixedly positioned above identification means 17a. A switch 19 is fixedly positioned approximately half-way between file items 16a and 16b when file item 16a is under casing 18 as seen in FIG. 1.

55 In FIG. 2 there is seen an enlarged view seen along lines 2—2 of FIG. 1 showing casing 18 with six identical transducer heads 21, 22, 23, 24, 25, and 26. Transducer heads 21 through 26 are aligned at approximately equally spaced intervals.

60 An enlarged showing of a side view of transducer head 21 (which is typical of the other transducer heads) is seen in FIG. 3. Transducer head 21 includes a magnetic

core with core sections 21a and 21b having extremities forming end faces 21c and 21d defining a non-magnetic operating gap therebetween, within which a non-magnetic spacer 21e is inserted. Inductance coil 21f which leads 21g and 21h and inductance coil 21i which leads 21j and 21k are both wound on said magnetic core to be inductively coupled to each other. Coils 21f and 21i are wound in the same direction and are symmetrically arranged with respect to the non-magnetic gap. When current flows in coils 21i and 21f, electromagnetic lines of flux are developed in core sections 21a and 21b which pass through the non-magnetic gap between end faces 21c and 21d. As is well known, these lines of flux spread in the space between end faces 21c and 21d as indicated by lines 21' seen in FIG. 3 to form a metallic sensing region. If a metallic member made of iron, aluminum, etc., is placed in the space indicated by lines 21', then eddy currents will be induced in the metallic member to effectively reduce the magnetic coupling between coils 21i and 21f. For an oscillating frequency of about 50 kilocycles as hereinafter stated in reference to the circuit diagram of FIG. 5, a metallic member made of ferrous material has been found to be preferable. Even though such a ferrous material is not a very good electrical conductor, it enables more electromagnetic flux to pass therethrough making the operation of the detector units more sensitive. A metallic member may be stated to be in the metallic sensing region of transducer head 21 when it is positioned within the space indicated by lines 21', to reduce the magnetic coupling between coils 21i and 21f in a certain desired amount.

Referring now again to FIG. 2, there is also seen therein card holder 15a with an inserted file item 16a carrying its identification means 17a, and switch 19. As also seen in FIG. 4, card holder 15a has two opposite sides 15a' and 15a'' resiliently joined at one edge to normally press against each other forming an elongated clasp or fastener. A vertical flange 20a extends from one end of card holder 15a. Switch 19 is normally open and has a push-button 19a actuatable by flange 20a to be pushed in to close switch 19. File item 16a, which is typical of the other illustrated file items, is seen to be a rectangular shaped card which may have certain desired information printed or written thereon. The bottom edge of file item 16a is inserted between sides 15a' and 15a'' of card holder 15a to be retained thereby in a vertical position as shown. Identification means 17a includes opposite sides 17a' and 17a'' resiliently joined at edge 17' to normally press against each other forming an elongated clasp or fastener. With the top edge of file item 16a inserted between sides 17a' and 17a'', identification means 17a is attached to file item 16a and thereby carried by it. Three aligned metallic members 31, 34, and 36 are also seen to extend from edge 17' of identification means 17a to be close to although not in physical contact with correspondingly positioned transducer heads 21, 24 and 26, respectively. As seen in FIGS. 2 and 4, the width of each metallic member approximates the width of the core of each transducer head, and the thickness of each metallic member approximates the thickness of the non-magnetic gap of each transducer head.

Referring now to FIG. 5 which shows a schematic circuit diagram of the electronics utilized in the system of the described embodiment, there is seen switch 19, indicating device 27, circuit 28, the schematic electrical equivalents of transducer heads 21 and 22, circuits 41 and 42 associated with transducer heads 21 and 22, and circuit 29. All of the electronics of FIG. 5 is contained within casing 18.

Circuit 41 includes a transistor 41a connected to operate as an oscillator. Lines 21h and 21g of coil 21f of transducer head 21 connect to the base of transducer 41a and to a +2 volt D.C. line 30a, respectively. Lines 21k and 21j of coil 21i of transducer head 21 connect to the collector of transistor 41a and to common line

30b respectively. Capacitor 41b across coil 21i provides a tuned circuit for the frequency of oscillations which may be about 50 kilocycles. The base of transistor 41a receives a forward bias of +2 volts D.C. by being connected to line 30a through coil 21f. The emitter of transistor 41a connects to ground through resistor 41b' which can be varied to control the level of oscillations. During the absence of a metallic member such as metallic member 31 in the proximity of the non-magnetic gap of transducer head, the regenerative signal induced in coil 21f by coil 21i causes transistor 41a to oscillate. The alternating excursions of the oscillations taken from the collector of transistor 41a are coupled by capacitor 41c to appear across resistor 41c'. The negative excursions of these oscillations pass through diode 41d to be filtered by capacitor 41e in order to develop a negative bias on the cathode gate of silicon controlled switch transistor 41f.

As for transistor 41f, its cathode connects to ground, its anode connects to +20 volt D.C. line 30c through resistors 41g and 41h, and its anode gate connects to line 30b through resistor 41i. When transistor 41a is oscillating, the negative bias maintained on the cathode gate of transistor 41f prevents it from conducting. In that event, the voltage on line 41j connected to the anode of transistor 41f will be at +20 volts D.C., and circuit 41 will be in its first state of operation as herein referred to. If the oscillations should be interrupted, then the negative bias voltage on capacitor 41e will discharge through resistor 41e' causing the voltage on the cathode gate of transistor 41f to rise to +2 volts. Transistor 41f will thereupon be fired and conduct. If oscillations should thereafter continue, transistor 41f will not as a result thereof be reset to operate in its first state of operation, but it will continue to conduct. After transistor 41f has been fired, the voltage on line 41j connected to the anode of transistor 41f will be near zero volt or effectively at zero volt, and circuit 41 will be in its second state of operation as herein referred to. Accordingly, the presence of +20 volts D.C. on line 41j indicates that transistor 41f has been caused to be non-conducting and at all times since then has been provided with a negative bias at its cathode gate to maintain its non-conducting state. If the voltage on line 41j is at zero, an interruption of the oscillations developed by transistor 41a has occurred.

In addition, transistor 41k is provided in circuit 41 which has its collector connected to ground through resistor 41n, its emitter connected to line 30c, and its base connected to the junction of resistors 41g and 41h. When the base of transistor 41k is at +20 volts D.C., i.e. when transistor 41f is not conducting, then neither will transistor 41k conduct, and the voltage on line 41m from load resistor 41n will be at zero volt. On the other hand, when transistor 41f conducts, then the positive voltage at the base of transistor 41k is reduced to allow transistor 41k to conduct thereby developing a voltage on line 41m that is approximately +20 volts D.C. Accordingly, it will be realized that the voltages on lines 41j and 41m will be the reverse of each other, i.e. when line 41j is at +20 volts then line 41m will be at zero volt, and vice versa.

The combination of transducer head 21 and its associated circuit 41 form a detector unit as herein referred to. Transducer head 21 is connected to circuit 41 so that its transistor 41a oscillates as above described as long as a metallic member such as metallic member 31 is not in its sensing region. When such a metallic member is so disposed, then a sufficient amount of magnetic decoupling between coils 21i and 21f of transducer head 21 results to cause a cessation of said oscillations. By way of example, the transistors of circuit 41 may be of the following types commonly designated by manufacturers thereof, to-wit: transistor 41a as type 2N3565, transistor 41f as type 3N58, and transistor 41k as type 2N404.

As is the case for transducer heads 21 and 22, circuit 42 is also seen to be identical to circuit 41 and corresponding parts thereof have the numeral designation of said 75 circuit together with the corresponding letter designations

of circuit 41. The combination of transducer head 22 with its associated circuit 42 form another detector unit. Although not shown in the drawings, circuits identical to circuits 41 and 42 are provided to be associated with transducer heads 23, 24, 25 and 26 to form other detector units therewith, each of these circuits are connected in the same manner to its associated transducer head and to lines 30a, 30b, and 30c, as seen in FIG. 5 for circuits 41 and 42. In addition, each of the circuits for transducer heads 23 through 26 have a pair of lines extending to circuit 29, such as lines 41j and 41m for circuit 41 and lines 42j and 42m for circuit 42.

In circuit 29, lines 41j and 41m connect to terminals 51a and 51b of switch 51. Movable arm 51c of switch 51 is connectable to either one of terminals 51a and 51b and connects to common line 29' through diode 51'. In addition, lines 42j and 42m connect to terminals 52a and 52b of switch 52. Movable arm 52c of switch 52 is connectable to either one of terminals 52a and 52b and connects to common line 29' through diode 52'. Furthermore, each of the pair of similar lines from the circuits associated with transducer heads 23 through 26 connect to a switch and diode to common line 29' in circuit 29, in an identical manner as above described for lines 41j and 41m of circuit 41 as well as for lines 42j and 42m of circuit 42.

Each of the diodes of circuit 29 act to electrically decouple any positive voltage on common line 29' from its connected circuit associated with each transducer head. For example, if circuit 41 is in its first state of operation and movable arm 51c is set to contact terminal 51b, any positive voltage on line 29' will not be able to pass through diode 51' to line 41m which is at zero volt. On the other hand, if circuit 41 is in its second state of operation and movable arm 51c is set to contact terminal 51a, the positive voltage on line 29' will not be able to pass through diode 51' to line 41j which is at zero volt. All of the other diodes of circuit 29 operate in the same manner.

The movable arms of the switches in circuit 29 can be set to contact either one of its pair of terminals in any desired predetermined arrangement. Accordingly, it will be realized that if any of the movable arms of the switches of circuit 29 connect to a line having +20 volts thereon, then common line 29' will also have +20 volts thereon. Also, it will be realized that only if all of the movable arms of the switches of circuit 29 are connected to lines having zero volt thereon, then common line 29' will have zero volt thereon. In the latter event, it can be stated that the states of operation of all the detector units coincide with the setting of the switches of circuit 29. Therefore, circuit 29 provides a common means capable of being connected to the detector units to produce a coincident signal when the detector units are in their first and second states of operation in a predetermined arrangement. In this case the coincident signal happens to be the condition of zero volt on common line 29'.

Circuit 28 is seen to include transistors 28a and 28b. The collector of transistor 28a connects to line 28c through relay coil 28d and resistor 28e. The collector of transistor 28b connects to line 28c through resistor 28f and connects to line 28g through relay coil 28h. Line 28g connects to line 30a. The emitters of transistors 28a and 28b are connected to line 28g. The bases of transistors 28a and 28b are connected to each other and to line 28g through resistor 28i and to line 29' through resistor 28j.

Switch 19 has a pushbutton represented by movable arm 19a which connects to the +20 volts D.C. on line 30c, and has a terminal 19b connected to line 28c of circuit 28. Switch 19 is normally open as shown in FIG. 5. Upon pushbutton 19a being depressed by the flange of each cardholder such as flange 20a of card holder 15a seen in FIG. 2, then movable arm 19a is caused to contact terminal 19b. Thereupon, the voltage on line 30c is applied to line 28c to activate circuit 28. When circuit 28 is so activated, then if line 29' is at +20 volts, transistor 28b will con-

duct to effectively short relay coil 28h preventing it from being energized and transistor 28a will also conduct to allow relay coil 28d to be energized. When relay coil 28d is energized, its contactors 28k which are normally closed as seen in FIG. 5 are thereupon opened. In addition, with circuit 28 activated, if line 29' is at zero volt, then both transistors 28a and 28b will remain non-conducting and relay coil 28h will thereupon be energized. When relay coil 28h is energized, its pair of conductors 28m and 28n are respectively opened and closed, the reverse of that seen in FIG. 5 which therein represents the condition when relay coil 28h is not energized.

Each time that switch 19 is closed, either relay coil 28d or relay coil 28h is energized causing either contactor 28k or 28m to be opened to remove the +20 volts on line 30c from line 30b. When the voltage is removed from line 30b, all the silicon controlled switch transistors (such as transistors 41f and 42f) will be extinguished, i.e. caused to be non-conducting. Accordingly, each time that switch 19 is closed, all the detector units are reset to operate in their stated first state of operation. In addition, whenever relay coil 28h is energized, the voltage on line 30c will also be applied through the then closed contactors 28n via line 27' to indicating device 27. Indicating device may be any devices responsive to the presence of the said voltage on line 27' to give any desired indication thereof.

In operation, motor 12 drives endless belt 10 around pulleys 11a and 11b to transversely move the file items with respect to the detector units. Each time a file item passes the detector units, switch 19 (the interval indication means) operates to apply a +20 volt pulse (the interval termination signal) to activate circuit 28 during this pulse. Circuit 28 is the interval responsive means which receives the +20 volt pulses to reset all the detector units to operate in their first states of operation. As each succeeding file item passes the detector units, its identification means with its metallic members will cause certain of the detector units to operate in their second states of operation. Accordingly, the combination of detector units read the arrangement of metallic members of each identification means. Thereafter, circuit 28 resets the detector units to enable them to again read the identification means of the next file item. When the arrangement of the metallic members correspond with the settings of the switches in common means 29, common means 29 will produce a coincident signal. Circuit 28 is also responsive to this coincident signal to provide a file item identifying signal when the coincident signal exists during the interval termination signal. Accordingly, the file items will be moved on endless belt 10 until the desired file item has been located as determined by the presence of the file item identifying signal.

As circuit 28 only operates during the existence of an interval termination signal from switch 19, perfect alignment of the file items and their identification means is not necessary for proper identification thereof in the system of this invention. The operation of circuit 28 is made to wait until each identification means has passed the detector units before producing a file item identifying signal. Accordingly, not all of the metallic members of each file item identification means need to be simultaneously detected by the combination of detector units. Circuit 28 prevents errors in identification due to such misalignment and therefore enables accurate identification of the file times in the system of this invention.

If desired, the identification means can have its metallic members arranged to represent a binary number. If the presence of a metallic member in alignment with a corresponding detector unit is considered to be number 1 in binary form, and the absence thereof considered to be zero, then the identification means 17a of FIG. 2 bears 100101 in binary form, if it is read from left to right as seen in FIG. 2. Each file item can have an

other arrangement of aligned metallic members, the different combinations thereof representing different identification numbers in binary form. It will also be realized that any number of detector units may be used with file items having identification means with metallic members in correspondingly aligned positions. Moreover, the file items utilized in the system of this invention can be of any shape or form, as long as its identification means coact with the detector units substantially as described.

Having described the invention, what is claimed as new is:

1. A file storage system comprising:
  - a plurality of spaced file items, each file item having an identification means including one or more metallic members;
  - a plurality of detector units, each detector unit having a metallic sensing region, and each detector unit having a first state of operation and changing to operate in a second state of operation after a metallic member is disposed in its sensing region;
  - means to move the file items with respect to the detector units to cause each metallic member of an identification means to pass through the sensing region of one of the detector units during a separate time interval;
  - a common means capable of being connected to the detector units to produce a coincident signal when the detector units are in their first and second states of operation in a predetermined arrangement;
  - an interval indication means operable after each file item passes the detector units to produce an interval termination signal; and
  - an interval responsive means responsive to each interval termination signal to reset the detector units causing all of them to operate in their first states of operation, and to produce a file item identifying signal when a coincident signal exists during an interval termination signal.
2. The file storage system defined in claim 1 wherein each detector unit includes a transducer head having a magnetic core with a non-magnetic gap forming a metallic sensing region, and having a first coil and a second coil wound on said magnetic core; an amplifier connected to said first and second coils to amplify a signal induced in the first coil and develop a regenerative signal in the second coil, the first and second coils being coupled to each other to cause the amplifier to oscillate, and to be responsive to the presence of a metallic member in its metallic sensing region to cause the amplifier to cease oscillating; and a detector circuit connected to the amplifier to provide one signal when the amplifier continues to oscillate during each of said intervals, and to provide another signal after the amplifier has ceased oscillating during each of said intervals.
3. A file storage system comprising:
  - a plurality of spaced file items, each file item having an identification means including one or more metallic members;
  - a plurality of detector units, each detector unit having a metallic sensing region, and each detector unit having a first state of operation and changing to operate in a second state of operation after a metallic member is disposed in its sensing region;
  - a common means capable of being connected to the detector units to produce a coincident signal when the detector units are in their first and second states of operation in a predetermined arrangement;
  - an interval indication means operable after each file item passes the detector units to produce an interval termination signal;
  - means to move the file items with respect to the detector units to cause each metallic member of an identification means to pass through the sensing region of one of the detector units in between interval termination signals; and

an interval responsive means responsive to each interval termination signal to reset the detector units causing all of them to operate in their first states of operation, and to produce a file item identifying signal when a coincident signal exists during an interval termination signal.

4. The file storage system defined in claim 3 wherein each detector unit includes a transducer head having a magnetic core with a non-magnetic gap forming a metallic sensing region, and having a first coil and a second coil wound on said magnetic core; an amplifier connected to said first and second coils to amplify a signal induced in the first coil and develop a regenerative signal in the second coil, the first and second coils being coupled to each other to cause the amplifier to oscillate, and to be responsive to the presence of a metallic member in its metallic sensing region to cause the amplifier to cease oscillating; and a detector circuit connected to the amplifier to provide one signal when the amplifier continues to oscillate in between interval termination signals, and to provide another signal after the amplifier has ceased oscillating in between interval termination signals.

5. A file storage system comprising: a plurality of file items, each file item having an identification means including one or more aligned metallic members; a plurality of detector units, each detector unit having a metallic sensing region, each detector unit having a first state of operation and changing to operate in a second state of operation after a metallic member is disposed in its sensing region; and means to move the file items with respect to the detector units to cause each metallic member of an identification means to pass through the sensing region of one of the detector units during a separate time interval, wherein each detector unit includes a transducer head having a magnetic core with a non-magnetic gap forming a metallic sensing region, and having a first coil and a second coil wound on said magnetic core; an amplifier connected to said first and second coils to amplify a signal induced in the first coil and develop a regenerative signal in the second coil, the first and second coils being coupled to each other to cause the amplifier to oscillate, and to be responsive to the presence of a metallic member in its metallic sensing region to cause the amplifier to cease oscillating; and a detector circuit connected to the amplifier to provide one signal when the amplifier continues to oscillate during each of said intervals, and to provide another signal after the amplifier has ceased oscillating during each of said intervals.

6. A file storage system comprising: a plurality of file items, each file item having an identification means including one or more aligned metallic members; a plurality of aligned detector units positioned to be substantially parallel with the aligned metallic members of each identification means, each detector unit having a metallic sensing region, and each detector unit having a first state of operation and changing to operate in a second state of operation after a metallic member is disposed in its sensing region; and means to move the file items with respect to the detector units to cause each metallic member of an identification means to pass through the sensing region of one of the detector units during a separate time interval, wherein each detector unit includes a transducer head having a magnetic core with extremities terminating in end faces in apposition to each other defining a non-magnetic gap forming a metallic sensing region, and having a first coil and a second coil wound on said magnetic core; an amplifier connected to said first and second coils to amplify a signal induced in the first coil and develop a regenerative signal in the second coil, the first and second coils being coupled to each other to cause the amplifier to oscillate, and to be responsive to the presence of a metallic member in its sensing region to cause the amplifier to cease oscillating; and a detector circuit connected to the

amplifier to provide one signal when the amplifier continues to oscillate during each of said intervals, and to provide another signal after the amplifier has ceased oscillating during each of said intervals.

7. An identifying system comprising: a transducer head having a magnetic core with a non-magnetic gap forming a metallic sensing region, and having a first coil and a second coil wound on said magnetic core to be responsive to the presence of a metallic member in the metallic sensing region to change the magnetic coupling between said coils; an amplifier connected to said first and second coils to amplify a signal induced in the first coil and develop a regenerative signal in the second coil; and a detector circuit connected to the amplifier to provide one signal when the amplifier oscillates during a time interval, and to provide another signal when the amplifier does not oscillate during said time interval.

8. An identifying system comprising: a transducer head having a magnetic core with extremities terminating in end faces in apposition to each other defining a non-magnetic gap forming a metallic sensing region, and having a first coil and a second coil wound on said mag-

netic core; an amplifier connected to said first and second coils to amplify a signal induced in the first coil and develop a regenerative signal in the second coil, the first and second coils being coupled to each other to cause the amplifier to oscillate, and to be responsive to the presence of a metallic member in its metallic sensing region to cause the amplifier to cease oscillating; and a detector circuit connected to the amplifier to provide one signal when the amplifier continues to oscillate during a time interval, and to provide another signal after the amplifier has ceased oscillating during said time interval.
